UNITED STATES PATENT OFFICE.

FREDERICK PEITER, OF CLEVELAND, OHIO, ASSIGNOR TO THE GAS MACHINERY COMPANY, OF CLEVELAND, OHIO, A CORPORATION OF OHIO.

COKE-OVEN.

1,146,442.

Specification of Letters Patent.

Patented July 13, 1915.

Application filed February 24, 1913. Serial No. 750,228.

To all whom it may concern:

Be it known that I, FREDERICK PEITER, a citizen of the United States, resident of Cleveland, county of Cuyahoga, and State of Ohio, have invented a new and useful Improvement in Coke-Ovens, of which the following is a specification, the principle of the invention being herein explained and the best mode in which I have contemplated applying that principle, so as to distinguish it from other inventions.

My invention relates to coke-ovens and particularly to that type known as regenerative or regenerator-coke-ovens.

The object of the invention is to provide a coke-oven of the above specified character which will be economical and efficient in its operation.

The said invention consists of means hereinafter fully described and particularly set forth in the claims.

The annexed drawings and the following description set forth in detail certain means embodying my invention, the disclosed means, however, constituting but one of various mechanical forms in which the principle of the invention may be applied.

In said annexed drawings:—Figure 1 is a longitudinal vertical section of a coke-oven embodying my invention and taken upon a plane passing through the axis of one of the coking-chambers. Fig. 2 is a transverse vertical section taken upon the plane indicated by line II—II in Fig. 1. Fig. 3 is a second transverse vertical section taken upon the plane indicated by the line III—III in Fig. 1. Fig. 4 is a vertical longitudinal section taken upon the plane indicated by line IV—IV in Fig. 5. Fig. 5 is a horizontal section taken upon the plane indicated by line V—V in Figs. 1 and 4.

The illustrated embodiment of my invention comprises the outer casing or structure A in which are formed a plurality of parallel coking-chambers A' which extend from front to rear in the usual manner and are provided at its extremities with removable closures A² and A³, by means of which the contents thereof may be discharged, as will be understood by those skilled in the art. Charging openings a a communicating with the top of each coking-chamber are provided and closed by means of suitable removable covers a' as shown in Fig. 1.

Extending from front to rear of the oven

and respectively adjacent to the two side walls of each coking-chamber, is a series of combustion-chambers B B' arranged in pairs, the reference letters B B and B' B' representing respectively alternately occurring pairs of these chambers as shown in Fig. 4. Vertical walls a² separate the adjacent pairs of chambers, and located intermediately of the two chambers of each pair is a vertical air-duct C. Openings a³ a³ in the walls a², Figs. 3 and 4, afford communication between adjacent chambers of adjacent pairs, these openings being located at the bottom of the combustion-chambers as shown.

Beneath each coking-chamber A' and parallel therewith is the horizontal flue D and laterally of the end series of combustion-chambers are formed similar flues D' D' as shown in Fig. 2. It will therefore be observed that each series of combustion-chambers has two flues D or D' placed laterally with reference to its sides as is clearly shown in said Fig. 2. Each air-duct communicates by means of branches c c, with one of these horizontal flues D or D', such communication occurring alternately on the part of the air-ducts between one series of combustion-chambers, with flues on opposite sides of such series as shown in Fig. 2. Taking one series of air-ducts from front to rear of the oven for an example, the first duct communicates with the flue on the right thereof, the second duct with the flue on the left thereof, the third duct with the same flue on the right thereof and so forth, all air-ducts in the same vertical longitudinal plane communicating in a like manner with the corresponding lateral flues D.

Beneath each flue is a regenerator E which extends longitudinally of the oven and each flue D communicates, by means of a vertical passage D², Fig. 1, with one end of a regenerator located below it. Such communication occurs alternately, that is for example, the flue on the extreme left communicates directly with the rear of the regenerator below it, the next and adjacent flue communicates directly with the front of its regenerator, the next with the rear of its regenerator and so forth. That end of each regenerator which is opposite the end which directly communicates with the flues D or D', is connected respectively with passages F F', by means of ducts f f as shown in Fig. 1.

These passages F F', are placed beneath the regenerators, are parallel with each other and extend transversely of the oven, and are so arranged that they may be connected either with a stack or with the atmosphere as may be desired.

The upper end of each combustion-chamber B or B' terminates some distance below the top of the casing as shown in Fig. 4, and each such chamber communicates with an auxiliary chamber B² by means of an opening b. Extending downwardly into the upper portion of each of these auxiliary chambers is a gas nozzle G. Lying horizontally upon opposite sides of the vertical axial plane of each series of combustion-chambers and in suitable depressions a⁴, Figs. 2, 3 and 5, are the fuel-gas supply pipes H H. All of the nozzles which discharge into the auxiliary chambers B² above the combustion-chambers B B, are connected to one of these pipes H, and all of the nozzles discharging into the chambers B² B² above the combustion-chambers B' B' are connected to the other of these pipes, and each such connection is controlled by means of a suitable manually operable valve h as shown in Figs. 3 and 4. The one end of one pipe H is connected with a header H' and the opposite end of the other pipe is connected with a header H². The passage of fuel-gas through these headers is controlled respectively by means of manually operable valves h' h², by means of which the supply of fuel-gas to all of the nozzles connected to all the pipes H may be cut off simultaneously, while such fuel-gas is permitted to flow simultaneously to all of the nozzles connected to the other pipes H. In addition to this control it will be noted that the flow from each nozzle may also be regulated independently of the flow from all of the other nozzles by means of the valves h.

In order to effectually close the upper portion of the auxiliary chambers B² B² bricks a⁵ are fitted therein and provided with apertures from which the nozzles extend as shown, and the extreme upper end of each of these chambers is closed by a suitable cover a⁶.

The air-ducts C extend upwardly to the top of the casing as shown and their upper ends are closed by suitable covers a⁷, Fig. 4. In the bottom of each such air-duct and opposite the branches c, is placed a slideable valve C' usually in the form of a fire-brick, by means of which the influx of air may be controlled. This valve is moved by means of a suitable rod inserted into the air-duct from the top after the cover a⁷ has been removed, as will be understood.

Affording communication between each combustion-chamber B or B', and the intermediate air-duct C are two openings c' c', two of these openings communicating with

each combustion-chamber as shown in Fig. 3. These openings are located upon opposite sides of the vertical axial plane of the openings b through which the fuel-gas enters the top of the combustion-chamber.

The above described device operates as follows:—Let it be assumed that the passage F' is connected with the stack and the passage F is connected with the atmosphere. The supply of fuel-gas is now turned off by means of the corresponding valve h' from header H², and the gas permitted, therefore, to pass into all the pipes H'. The nozzles connected with these latter pipes discharge gas into the pairs of combustion-chambers B B, no such discharge taking place into the chambers B' B'. The air-ducts C communicating with these chambers B B are therefore connected with those flues D which are in communication with those regenerators which are connected with the passage F and atmospheric air is therefore supplied to these combustion-chambers B B. Upon ignition of the gas and air, the mixture burns in the chambers B B and the gases of combustion pass out through the openings a³ a³ into the adjacent combustion-chambers of the adjacent pairs B' B', these latter therefore serving under these conditions, as passages for the gases of combustion. From these passages B' therefore these gases of combustion pass into the air-ducts C which are located between the said chambers or passages B' B' and thence into the corresponding flues D. From the latter these hot gases pass into the regenerators connected with these flues, through these regenerators and thus out through the passage F' and into the stack from whence they are discharged into the atmosphere. In this manner alternate regenerators are heated by the gases of combustion and the coking-chambers are at the same time heated to the temperature necessary to produce the coking operation as will be readily understood, alternate pairs of combustion-chambers in each series, however, furnishing the heat for this coking operation.

After a given length of time has elapsed the direction of travel of the gases is reversed. To effect this reversal, the passage F' is now connected with the atmosphere and the passage F with the stack, the arrangement for this purpose (not shown) being of any well-known or accepted design, such as is familiar to those skilled in the art. The fuel-gas is now shut off from the header H' by means of the valve h' associated therewith, and turned into the header H' by means of its valve h'. Such fuel-gas is therefore supplied to those nozzles, which in the previously described operation, were inactive. Fuel-gas is therefore discharged into the previously inactive combustion-chambers which were serving as outlet-

ducts for the gases of combustion. Those air-ducts which were serving as outlets in the said previously described operation are now discharging air into these active combustion-chambers, and the mixture may therefore be ignited and burned. The gases of combustion thus produced take a path similar to that previously described, the formerly active combustion-chambers now 5 acting as outlet ducts for the gases of combustion, as do also the formerly active air-ducts. Those regenerators which in said previously described operation received and were heated by the gases of combustion, are 10 now traversed by the incoming air supply and the formerly inactive regenerators are now being heated by the said gases. The incoming air, however, passes through the regenerators which have been heated in the 15 former operation by the gases of combustion, thus conserving heat as required.

After the lapse of a second required period of time the operation is again reversed as will be readily understood.

25 The influx of air into the regenerators from either of the passages F or F' is regulated by means of a sliding valve J, Fig. 1, usually in the form of a fire-brick which may be reached and manipulated from the 30 exterior through an aperture a⁸ provided with a removable closure a⁹.

By means of the above described arrangement of parts, I obtain a coke-oven which is economical and efficient in its operation.

35 A particular advantage embodied in such construction lies in the arrangement of the fuel-gas supply pipes at the top of the oven whereby each nozzle may be provided with a readily accessible valve so that the supply 40 of fuel to each combustion-chamber, and therefore the combustion itself therein, may be regulated and controlled independently of every other combustion-chamber.

A further specific advantage of said construction resides in the arrangement of the 45 regenerators E, the ducts D and the passages F and F'. Said arrangement permits of the use of either the passage F or F', as the case may be, as an inlet for atmospheric 50 air. These passages are also, as described, used for the discharge of the gases of combustion after leaving the regenerators, and therefore absorb more or less of the residual 55 heat from these gases after leaving the regenerators. When either of these passages is used as an air-inlet therefore, the atmospheric air is heated to some degree even before it enters the regenerators, an additional amount of heat which would otherwise be 60 dissipated being thus conserved.

By arranging the combustion-chambers so that the air inlet discharges in the vicinity of the fuel-gas inlet, providing two air-inlets to each combustion-chamber, and 65 arranging these inlets laterally with respect

to the fuel-gas inlet, as described, a more thorough and intimate mixture of the gases is obtained in the combustion-chambers with consequent better combustion than would otherwise be obtained. 70

Having fully described my invention, what I claim and desire to secure by Letters Patent is:

1. In a coke-oven, the combination of a 75 coking-chamber; a plurality of combustion-chambers adjacent to one side-wall of said coking-chamber; a plurality of air-ducts, one such duct located between successively occurring pairs of combustion-chambers and communicating with each member of such pairs at the top thereof; adjacent chambers of adjacent pairs of such chambers communicating with each other at the bottom; and a fuel-gas supply communicating with each 80 combustion-chamber at the top. 85

2. In a coke-oven, the combination of a coking-chamber; a plurality of combustion-chambers adjacent to one side wall of said coking-chamber; a fuel supply with which 90 said coking-chamber is in communication; a plurality of air-ducts, one such duct located between successively occurring pairs of combustion-chambers and communicating with each member of such pairs at the top thereof; adjacent chambers of such pairs of 95 combustion-chambers communicating with each other at the bottom; and means for controlling said fuel supply so as to simultaneously cut off one of the sets of alternately occurring pairs of combustion-chambers 100 therefrom.

3. In a coke-oven, the combination of an outer inclosed casing, a coking-chamber formed within the latter and extending longitudinally therethrough; two series of 105 combustion-chambers respectively adjacent to the two side-walls of said coking-chamber, each series comprising a plurality of pairs of combustion-chambers having an air-duct between the members of each pair and communicating therewith at the top, adjacent chambers of adjacent pairs communicating with each other at the bottom; longitudinal bottom horizontal flues each placed laterally with reference to the sides of each 110 series of combustion-chambers respectively; alternate air-ducts of each series being connected with one of said flues; a regenerator beneath each such flue; one end of each of the latter communicating with one of said 115 regenerators, such communication occurring alternately at the front and rear of the oven; two transversely extending passages communicating respectively with that end 120 of each regenerator opposite that with which 125 a flue communicates.

4. In a coke-oven, the combination of an outer inclosing casing; a vertical combustion-chamber formed within said casing; a 130 fuel-gas opening communicating with the

top of said combustion-chamber; a vertical air-duct extending to the top of the casing and provided with a closure for its upper end; said air-duct provided with a horizontal branch at the bottom thereof; and a slideable valve in the bottom of said duct adapted to control the passage of fluid through said branch.

5. In a coke-oven, the combination of a coking-chamber; a plurality of combustion-chambers adjacent to one side wall of said coking-chamber and having an outlet for the gases of combustion; a plurality of air-ducts, one such duct being placed intermediate of the two chambers of each succeeding pair of combustion-chambers and communicating with the top of each thereof; two horizontal fuel-gas supply pipes above such combustion-chambers provided with downwardly extending nozzles, each of said nozzles being in communication with the top of one of said combustion-chambers; all of the nozzles in communication with alternate pairs of combustion-chambers being connected to one of said pipes and the other nozzles to the other of said pipes; and means for cutting the fuel-gas off from or admitting such gas into each of said pipes independently of the other.

20 6. In a coke-oven, the combination of a

coking-chamber; a plurality of combustion-chambers adjacent to one side wall of said coking-chamber, each having an outlet for the gases of combustion; a plurality of air-ducts, one such duct being placed intermediate of the two chambers of each succeeding pair of combustion-chambers and communicating with the top of each thereof; two horizontal fuel-gas supply pipes above such combustion-chambers provided with downwardly extending nozzles, each of said nozzles being in communication with the top of one of said combustion-chambers; all of the nozzles in communication with alternate pairs of combustion-chambers being connected to one of said pipes and the other nozzles to the other of said pipes; and means for cutting the fuel-gas off from or admitting such gas into each of said pipes independently of the other; and means for controlling the flow of said gas through each of said nozzles independently of all of the other of said nozzles.

Signed by me, this 13th day of February, 1913.

FREDERICK PEITER.
